(57) **CLAIM**

The ornamental design for a tankless hot water heater transducer as shown and described.

DESCRIPTION

FIG. 1 is a front view of the first embodiment of a tankless hot water heater having the new design for a transducer configuration.

FIG. 2 is a first perspective side view of the first embodiment of a tankless hot water heater having the new design for a transducer configuration.

FIG. 3 is a second perspective side view of the first embodiment of a tankless hot water heater having the new design for a transducer configuration.

FIG. 4 is a side view of the first embodiment of a tankless hot water heater having the new design for a transducer configuration.

FIG. 5 is a top view of the first embodiment of a tankless hot water heater having the new design for a transducer configuration.

FIG. 6 is a bottom view of the first embodiment of a tankless hot water heater having the new design for a transducer configuration.

FIG. 7 is a front view of the second embodiment of a tankless hot water heater having the new design for a transducer configuration.

FIG. 8 is a first perspective side view of the second embodiment of a tankless hot water heater having the new design for a transducer configuration.

FIG. 9 is a second perspective side view of the second embodiment of a tankless hot water heater having the new design for a transducer configuration.

FIG. 10 is a side view of the second embodiment of a tankless hot water heater having the new design for a transducer configuration.

FIG. 11 is a top view of the second embodiment of a tankless hot water heater having the new design for a transducer configuration.

FIG. 12 is a bottom view of the second embodiment of a tankless hot water heater having the new design for a transducer configuration.

FIG. 13 is a front view of the third embodiment of a tankless hot water heater having the new design for a transducer configuration.

(Continued)

FIG. 14 is a first perspective side view of the third embodiment of a tankless hot water heater having the new design for a transducer configuration.

FIG. 15 is a second perspective side view of the third embodiment of a tankless hot water heater having the new design for a transducer configuration.

FIG. 16 is a side view of the third embodiment of a tankless hot water heater having the new design for a transducer configuration.

FIG. 17 is a top view of the third embodiment of a tankless hot water heater having the new design for a transducer configuration.

FIG. 18 is a bottom view of the third embodiment of a tankless hot water heater having the new design for a transducer configuration.

FIG. 19 is a front view of the fourth embodiment of a tankless hot water heater having the new design for a transducer configuration.

FIG. 20 is a first perspective side view of the fourth embodiment of a tankless hot water heater having the new design for a transducer configuration.

FIG. 21 is a second perspective side view of the fourth embodiment of a tankless hot water heater having the new design for a transducer configuration.

FIG. 22 is a side view of the fourth embodiment of a tankless hot water heater having the new design for a transducer configuration.

FIG. 23 is a top view of the fourth embodiment of a tankless hot water heater having the new design for a transducer configuration.

FIG. 24 is a bottom view of the fourth embodiment of a tankless hot water heater having the new design for a transducer configuration.

FIG. 25 is a front view of the fifth embodiment of a tankless hot water heater having the new design for a transducer configuration.

FIG. 26 is a first perspective side view of the fifth embodiment of a tankless hot water heater having the new design for a transducer configuration.

FIG. 27 is a second perspective side view of the fifth embodiment of a tankless hot water heater having the new design for a transducer configuration.

FIG. 28 is a side view of the fifth embodiment of a tankless hot water heater having the new design for a transducer configuration.

FIG. 29 is a top view of the fifth embodiment of a tankless hot water heater having the new design for a transducer configuration; and,

FIG. 30 is a bottom view of the fifth embodiment of a tankless hot water heater having the new design for a transducer configuration.

The broken lines in the figures show portions of the tankless hot water heater transducer that form no part of the claimed design.
